UNITED STATES PATENT OFFICE.

WILLIAM MARCROFT, OF PROVIDENCE, RHODE ISLAND, ASSIGNOR TO UNIVERSAL WINDING COMPANY, OF PORTLAND, MAINE, A CORPORATION OF MAINE.

TENSION DEVICE.

1,078,448.

Specification of Letters Patent. Patented Nov. 11, 1913.

Application filed May 22, 1912. Serial No. 699,002.

To all whom it may concern:

Be it known that I, WILLIAM MARCROFT, a citizen of the United States, residing at Providence, in the county of Providence and 5 State of Rhode Island, have invented certain new and useful Improvements in Tension Devices, of which the following is a specification.

My invention relates to tension-devices for 10 use in applying tension to yarn, thread or the like in delivering the same to winding machines or other textile apparatus.

My improvement relates particularly to 15 that class of devices generally called plate or grid tensions in which the yarn is arranged to draw between two grid-like plates adapted to be pressed against the yarn to apply resistance to its draft.

The object of my improvement is to provide 20 a tension-grid or plate having a practically indestructible bearing surface, capable of resisting the abrasive action of hard-twisted threads and fine silk, and adapted to prevent vibration and chattering of the 25 grids when the yarn is drawn rapidly across their faces.

The invention is fully described in the following specification, illustrated by the accompanying drawings, in which:

30 Figure 1 is a side elevation of my improved tension-device, showing the grid-members assembled in the supporting bracket; Fig. 2, an end elevation of the same, showing the relation of the opposed 35 grids and the manner in which the yarn draws between them; Fig. 3, a perspective view of the left-hand grid-plate; Fig. 4, an opposite perspective view of the right-hand plate; Fig. 5, a perspective view of one of 40 the grids which are supported on the plates.

Referring to Figs. 1 and 2, B designates 45 a bracket having an arm b, which may be attached to the frame of the winding or other machine, and an upright b' formed with horizontally disposed end members or lugs b² and b³. A vertical rod R is supported in the lugs b² and b³ and on this are hinged the two main tension elements or grid-plates T and T'. The plates T and T' 50 are preferably constructed of sheet-metal and are formed with ears t, t', t² and t³, bent at right-angles to the main portions of the plates at the upper and lower extremities of

their rear edges. Suitable holes t⁴ are provided in the ears to receive the rod R on 55 which the plates are supported.

The plate T is arranged to swing on the rod R; and the plate T' is preferably secured in a fixed position by means of a screws extending through a slot t⁵ in an extension t⁶ of the plate and screwed into the upright b' of the bracket B, see Fig. 1. The upper ear t of the grid T extends outward in an arm t⁷ through which this member is operated to swing it toward the fixed member T'. Any suitable arrangement of springs or weights may be used to press the hinged plate toward the fixed plate, but I have preferred to show a cord d fastened to the arm t⁷ by means of the hole t⁸ at the 60 end of the arm and led over a small roll or pulley p pivoted at p' on the bracket B, see Figs. 1 and 2. At the opposite end of the cord is a hook h engaging a hole at the end of a pin o, and secured to the bottom of the pin is a disk-shaped weight w. Additional weights w' can be strung on the pin o to increase the pressure exerted through the arm t⁷ to swing the member T toward the member T'. 65

Secured on the inner faces of the plates, T and T' are two grid-members G and G' of the form illustrated in Fig. 5. The grids G and G' are preferably constructed of porcelain, glass or some other similar vitreous substance to render their bearing faces impervious to the abrasive action of the thread or yarn. Their inner faces are corrugated or fluted with transverse ribs g and g', etc., preferably spaced alternately or arranged in a staggered relation when the grids are opposed to each other on the plates T and T'. The grids G and G' are secured 80 in position on the plates in the ingenious manner now described: At the top and bottom edges of each plate a portion of the metal is folded over and bent down close to the main portion to form abutments t⁹, t¹⁰, etc., see Fig. 3. These abutments engage the top and bottom edges of the grids and hold 85 them in position vertically of the plates. Referring to Fig. 5, the longitudinal edges g² and g³ of the grids are preferably beveled at acute angles to their rear faces which lie next to the inner plane faces of the plates T, T', and means are provided to lap over 90

95 the edges g² and g³ of the grids. The longitudinal edges g¹ and g⁴ of the grids are beveled at acute angles to the rear faces which lie next to the inner plane faces of the plates T, T', and means are provided to lap over 100 the edges g¹ and g⁴ of the grids. Referring to Fig. 5, the longitudinal edges g² and g³ of the grids are beveled at acute angles to the rear faces which lie next to the inner plane faces of the plates T, T', and means are provided to lap over 105 the edges g² and g³ of the grids.

and impinge upon these beveled faces to secure the grids in place. These means are as follows: The outer or front edge of each plate is formed with a strip t^{10} or portion of the metal folded over at the same angle as the beveled edge g^2 of the grid G and the latter is adapted to lie under this fold. The opposite or rear edge of the grid is held by a wire clamp C. The clamp C is preferably formed with a main, bow-shaped portion c having two legs c' , c' bent over in the hooked ends c^2 , c^2 . The ends c^2 , c^2 are adapted to hook over the rear faces of the plates T, T' and impinge upon the rear beveled edges g^3 of the grids G, G'. The bow-shaped portion c of the clamp C is then sprung under an ear or projection t^{11} which is punched out and bent up from the outer face of the plates T and T'.

In applying the grid to the plate the front beveled edge g^2 is simply slid under the folded edge t^{10} and the hooked ends c^2 , c^2 of the clamp C hooked over the rear edge g^3 of the grid. The bowed portion c of the clamp C is then sprung out and under the ear t^{11} and thus the grid is clamped snugly in place with its upper and lower edges abutting the folded portions t^9 , t^9 of the plate T.

The plates T and T' are held in the frame B as previously described and the grids G and G' are supported with their corrugated faces opposed to each other and with the ribs g and g' alternating. The yarn y is led up between the two grids and draws across their faces with the hinged grid G tending to press the yarn into the corrugations on the fixed grid G'. The grids are formed with a relatively large number of cross-ribs so that the yarn has numerous contacting points along their faces and, therefore, it has been found that it is not necessary to apply extreme pressure to force the movable grid toward the fixed grid to cause resistance to the draft of the yarn.

That is to say, since the grids bear upon the yarn at so many points, a considerable resistance will be applied to its draft without the necessity of forcing it to travel in an extremely sinuous course.

Referring to Fig. 2, the yarn is shown as having an almost straight course between the grids and the very slight sinuosity shown has been found sufficient in most cases to apply the maximum tension required.

For this reason my new device shows marked improvement over previous arrangements because the yarn is not subjected to so much friction, since it bears only on the relatively narrow outer edges of the ribs. Furthermore, it has been demonstrated that the less sinuous or tortuous the course of the yarn is made, the less tendency there is for the movable tension plate to vibrate or chatter, and hence the tension applied to the yarn will

be more constant and uniform. It is also to be noted that the grid member, being solid and constructed of a relatively heavy material, adds considerably to the weight of the tension member and this extra weight tends to increase its stability. In other words, the movable member possesses considerable inherent inertia, owing to its increased weight, and this acts to prevent vibration or chattering of the grid, so that the uniformity of tension is further enhanced.

My new device not only provides for improved results in tensioning the yarn, but the structure and arrangement of the parts also add greatly to its durability and, furthermore, allow for convenient replacing of the porcelain should the latter become broken or worn. As before explained, the grids can be easily and readily slipped into and out of position on the plates by simply adjusting the clamping device, which requires but a moment's manipulation. When a grid becomes worn or broken it is not necessary to replace the whole tension member, but merely the grid itself, the cost of which is comparatively slight. In addition, the grids being made of glass or porcelain, they will outlast several metal grids or plates and the multiplicity of the bearing points for the yarn still further adds to their life.

Various modifications might be made in the form and arrangement of the parts of the device without departing from the spirit or scope of the invention; therefore, without limiting myself to the exact construction shown, what I claim is:

1. In a tension-device, the combination with two tension-plates arranged to press upon the yarn running between them, of rectangular grid-members of vitreous material secured to the inner faces of the tension-plates and arranged to present opposite bearing surfaces to the yarn.

2. In a tension-device, the combination with two tension-plates arranged to press upon the yarn running between them, of grid-members constructed of vitreous material and formed with transverse ribs projecting from their opposed faces and means to secure said grids to the inner faces of the tension-plates.

3. In a tension-member for tension-devices, the combination with a plate T having portions folded over along its edges, and a grid G adapted to lie against the face of the plate with its edges engaged by the folded portions of the latter to hold it in position thereon.

4. In a tension-member for tension-devices, the combination with a plate T having abutments t^9 , t^9 , along its top and bottom edges and a folded strip t^{10} along its

outer edge, of a grid G adapted to be held against the face of the plate with its upper and lower edges engaging the abutments t^9 , t^9 , and its outer edge lying under the strip t^{10} , and means to secure the grid in position on the plate.

5. In a tension-member for tension-devices, the combination with a plate T having portions of its top and bottom edges folded over to form abutments t^9 , t^9 , and a portion t^{10} of its outer edge folded over at an angle to its face, of a grid G adapted to be held on the plate with its top and bottom edges engaging the abutments t^9 , t^9 and its outer edge lying under the folded portion t^{10} , and a spring clamp arranged to secure the rear edge of the grid to the plate.

6. In a tension-member for tension-devices, the combination with a plate T, of a grid G adapted to be secured to the face of the plate, means engaging the edges of the grid to locate it on the plate, and a clamp C adapted to hook over the edge of the plate and impinge upon the edge of the grid.

25 7. In a tension-member for tension-devices, the combination with a plate T, of a grid G adapted to be secured to the face of

the plate, means engaging the edges of the grid to locate it on the plate, a spring clamp C having portions c' , c' , hooked over the edge of the plate and terminating in the ends c^2 , c^2 , overlying the edge of the grid and means to secure the clamp to the plate.

8. In a tension-member for tension-devices, the combination with a plate T having portions of its top and bottom edges folded over to form abutments t^9 , t^9 , a portion t^{10} of its outer edge bent up to form a trough, and an ear t^{11} bent up adjacent the center of the plate, of a grid G adapted to be held against the face of the plate with its top and lower edges engaging the abutments t^9 , t^9 , and its outer edge lying under the fold t^{10} , and a wire clamp C having a bow-shaped portion c adapted to hook under the ear t^{11} and two hooked ends c' , c' , arranged to hook over the rear edge of the plate and impinge upon the edge of the grid.

In testimony whereof I affix my signature in presence of two witnesses.

WILLIAM MARCROFT.
